VEHICLE ARM REST

George W. Vissers, 2022 Windsor, Peoria, IL 61604

Filed Feb. 11, 1974, Ser. No. 441,113

Term of patent 14 years

Int. Cl. D6—99; D12—16

U.S. Cl. D12—155

FIG. 1 is a perspective view of a vehicle arm rest showing my new design, it being understood that the broken lines are for illustrative purposes only;

FIG. 2 is an end elevational view thereof opposite that shown in FIG. 1 to an enlarged scale;

FIG. 3 is a top plan view thereof to an enlarged scale;

FIG. 4 is a front elevational view thereof to an enlarged scale;

FIG. 5 is a bottom plan view thereof to an enlarged scale; and

FIG. 6 is a rear elevational view thereof to an enlarged scale.

I claim:

The ornamental design for a vehicle arm rest, as shown.
